[57] **CLAIM**

The ornamental design for a doll, as shown and described.

DESCRIPTION

FIG. 1 is a perspective view of a doll showing my new design;

FIG. 2 is a top plan view thereof;
FIG. 3 is a bottom plan view thereof;
FIG. 4 is a front elevational view thereof;
FIG. 5 is a right side elevational view thereof;
FIG. 6 is a rear elevational view thereof;
FIG. 7 is a left side elevational view thereof;
FIG. 8 is a perspective view of a second embodiment of a doll;
FIG. 9 is a top plan view thereof;
FIG. 10 is a bottom plan view thereof;
FIG. 11 is a front elevational view thereof;
FIG. 12 is a right side elevational view thereof;
FIG. 13 is a rear elevational view thereof;
FIG. 14 is a left side elevational view thereof;
FIG. 15 is a perspective view of a third embodiment of a doll;
FIG. 16 is a top plan view thereof;
FIG. 17 is a bottom plan view thereof;
FIG. 18 is a front elevational view thereof;
FIG. 19 is a right side elevational view thereof;
FIG. 20 is a rear elevational view thereof;
FIG. 21 is a left side elevational view thereof;
FIG. 22 is a perspective view of a fourth embodiment of a doll;
FIG. 23 is a top plan view thereof;
FIG. 24 is a bottom plan view thereof;
FIG. 25 is a front elevational view thereof;
FIG. 26 is a right side elevational view thereof;
FIG. 27 is a rear elevational view thereof; and,
FIG. 28 is a left side elevational view thereof.
The broken line showing of the face and hair features in FIGS. 8-14 and FIGS. 22-28 is for illustrative purpose only and forms no part of the claim.
